tion of Delaware

Original application February 25, 1943, Serial No.
477,167. Divided and this application October
30, 1943, Serial No. 508,332

9 Claims. (Cl. 250—13)

1

This application is a division of my copending U. S. application, Serial Number 477,167, filed February 25, 1943, entitled Ultra high frequency apparatus.

This invention relates generally to ultra-high frequency apparatus and more particularly to duplex switching apparatus for controlling simultaneously separate power and signal circuits applied to different components of a communication system.

In ultra-high frequency communication systems it is often desirable to control simultaneously the application of potentials derived from a power source to a signal generator and to isolate selectively a receiver from a signal source. Due to peculiarities inherent in ultra-high frequency apparatus, conventional switching means are seldom entirely satisfactory due to undesired reactive components which are thus introduced into the associated circuits. The instant invention contemplates the use of a current discharge device which may be keyed to provide a conductive path for connecting the power source to the signal generator while simultaneously presenting an open circuit to the signal path between the received signal source and the signal receiver. Various modifications of the invention will be described in detail hereinafter. However, all involve the common feature of providing simultaneous control of a current discharge path and a wave transmission path, such as, for example, a wave guide or a resonant chamber. This feature permits higher power control since it substantially eliminates the power surge, or "spike" introduced into the wave transmission path when the wave path alone is keyed.

Among the objects of the invention are to provide a new and improved method of and means for providing simultaneous switching of a power source and a wave transmission path. Another object of the invention is to provide an improved method of and means for providing a duplex ultra-high frequency switching device which comprises a current discharge path for a power source and a wave attenuator for a signal source. Another object of the invention is to provide an improved method of and means for controlling simultaneously the conductivity of a power transmission circuit and the attenuation of an ultra-high frequency wave transmission circuit. Still another object of the invention is to provide an improved method of and means for controlling simultaneously a power circuit and a wave transmission circuit through a dielectric wave guide. A further object of the invention is to provide an

2

improved method of and means for controlling simultaneously a power circuit and a wave transmission circuit between a plurality of resonant chambers in an ultra-high frequency circuit. A further object is to provide an improved method of and means for controlling a power circuit and an ultra-high frequency wave transmission circuit between two resonant chambers whereby said control is provided by a current discharge path between said chambers. A further object is to provide an improved method of and means for controlling a power circuit and an ultra-high frequency wave transmission circuit between two resonant chambers whereby said control is provided by an ionized path between said chambers.

Still another object of the invention is to provide an improved switching device for a power circuit and an ultra-high frequency circuit including a magnetron wherein said switching means includes a wave transmission circuit having a gaseous discharge path which may be keyed to provide an ionized path transversely across the wave transmission path, and in which said ionization is interrupted by means of variations in the potential applied to the magnetron.

The invention will be described in greater detail by reference to the accompanying drawings of which Figure 1 is a block diagram of one embodiment of the invention; Figure 2 is a cross-sectional view of an embodiment of the invention; Figure 3 is a cross-sectional view along the line AA of Figure 2; Figure 4 is a cross-sectional view of a modification of the invention; Figure 5 is a cross-sectional view of another modification of the invention; and Figures 6 and 7 are schematic circuit diagrams of modifications of the circuit described in Figure 1. Similar reference numerals are applied to similar elements throughout the drawings.

Referring to Figure 1, a transmitter 1 is supplied with operating potential from a transmitter power source 2 through a duplex switching device 3 of any of the types to be described in detail hereinafter. An antenna, or other signal source, 4 is connected to the input of a wave transmission circuit 5 such as, for example, a wave guide or a coaxial transmission line. The wave transmission circuit 5 also is connected through the duplex switching device 3 to a signal responsive device such as a radio receiver 6. A source of keying pulses 7 is connected to the duplex switching device 3. When a keying pulse from the keying source 7 is applied to the duplex switch 3, the power circuit from the power source 2 is completed through the switch 3 to the trans-

mitter 1. Simultaneously, the wave transmission circuit 5 is effectively interrupted to isolate the receiver 6 from the signal source 4. During the intervals between keying pulses from the keyer circuit 7, the power circuit from the transmitter power source 2 to the transmitter 1 is interrupted at the switch 3, while the wave transmission circuit through the transmission line 5 is completed from the signal source 4 to the signal receiver 6.

Figure 2 includes a section of wave guide 5 having a projection 6 extending transversely across a portion of the wave path. The wave guide is entirely enclosed within an evacuated envelope 10. Opposite the projection 6 is a second projection 8 comprising a cathode surface which is heated by a heater winding 9. A grid element 11 is disposed in the aperture formed in the guide between the cathode 8 and the projection 6. Separate leads are brought out through seals for the cathode, heater, grid and wave guide elements.

It should be understood that the device just described constitutes a thermionic discharge tube in which the projection 6 represents the anode of the tube. The shape of the aperture formed between the cathode and the anode elements of the discharge tube may be more clearly seen from the cross-sectional view shown in Figure 3. The aperture thus formed constitutes a resonant aperture of the type described in detail in the pending application of William D. Hershberger, Serial Number 477,176, filed February 25, 1943. Capacitive elements 12, 13 are disposed adjacent the supports of the grid 11, to bypass effectively the ultra-high frequency current components induced therein.

In operation, if the grid electrode 11 is biased negatively with respect to the cathode 8, and the anode 6 is positive with respect to the potential on the cathode 8, substantially no electron discharge will occur across the gap formed between the cathode and anode. Since the aperture is resonant at the wave transmission frequency, it provides an efficient transfer path through the wave guide 5 for waves introduced into the wave guide. However, if a positive potential is applied to the grid electrode 11, such as keying pulses from the keyer circuit 7, a current discharge path occurs across the gap between the cathode 8 and the anode 6 which effectively changes the resonant characteristics of the resonant aperture formed thereby. This change in resonance effectively blocks wave transmission through the wave guide, while it also provides a conductive path from the cathode 8 to the anode 6 which may be utilized for the transmission of power from the power source 2 to the transmitter 1.

It should be understood that the envelope 10 may be evacuated to form a vacuum type thermionic tube within the wave guide, or it may be filled with an inert gas at low pressure to provide a tube of the Thyratron type of gaseous discharge tube. If the tube just described is of the vacuum type, effective keying of any type of transmitter power source may be accomplished by means of positive keying pulses derived from the keyer circuit 7, providing a normal negative bias is applied to the grid 11. However, if the tube thus formed is of the Thyratron type, the circuit may only be keyed "on" by the positive keying pulses, and interruption of the discharge path must be accomplished by reducing the positive potential applied to the anode 6. Such a condition will prevail if the transmitter power source

provides alternating potentials or pulsating potentials of varying voltage between some predetermined maximum and zero value. Preferably, the ends of the wave guide 5 should extend as closely as possible to the envelope 10 in order that the device may be coupled efficiently to external transmission circuits.

Referring to Figure 4, a device of the general type described in Figures 2 and 3 includes two resonant chambers 21, 22 to which transmission lines 23, 24, respectively, are coupled through the envelope 10. A wave transmission path 25 extends between the resonant chambers 21, 22. The flat side 26 of this transmission wave path may be considered to be the anode of the current discharge device. A connection to the anode is brought out through a suitable seal in the envelope 10. A grid structure 27 and a cathode 28, heated by a heater 29, form the opposite boundary of the wave transmission path 25.

The operation of the device shown in Fig. 4 is similar to that of the device of Figures 2 and 3, except that the wave transmission through the path 25 is blocked effectively by the conductive path formed by the current discharge between the cathode 28 and the anode 26. The input line 23 is coupled to the first resonant cavity 21 through a coupling loop 20. The output transmission line 24 is coupled to the second resonant cavity 22 by means of a second coupling loop 30. It should be understood that the current discharge, whether electronic or ionic, does not affect substantially the resonance of the wave transmission path 25 as in Figures 2 and 3, but does provide an effective wave reflecting surface between the resonant cavities because of the conductive discharge path. Suitable leads to the heater, cathode, and grid electrodes may be brought out of the envelope 10 through a second seal therein.

Figure 5 discloses a device similar to that of Figure 4 with the exception that the discharge path occurs as a spark between the electrodes 26 and 28 which define the wave transmission path between the resonant chambers 21 and 22. This modification may also be evacuated or may contain an inert gas at low pressure.

In all of the devices described heretofore, it should be understood that the wave transmission path is through the particular wave transmission device described, while the power transmission path is between the cathode and anode or current discharge electrodes. It should also be understood that in each of the modifications described, the occurrence of a current discharge, whether electronic or ionic, will provide a conducting path which will complete the circuit between the power source and the transmitter, while simultaneously effectively blocking the transmission of signal waves through the device from the signal source to the signal receiver.

Figure 6 is a schematic circuit diagram of one application of any of the devices described heretofore wherein the duplex switch 40 of the Thyratron type may be utilized to control the anode potential to a magnetron 50. Keying pulses, derived from a keyer circuit 7, apply a positive bias to the grid of the switching tube 40 which initiates a current discharge to complete the anode circuit of the magnetron 50. However, the magnetron in this instance is driven by positive pulses 51, which are derived from a preceding tube 52 through a coupling capacitor 53. Since the positive pulse 51 returns to zero level, the current discharge through the switching tube 40 thereupon

will cease, and the circuit will key-off the transmitter, and key-on the associated receiver, until the next keying pulse from the keyer circuit 1 is applied to the grid of the switching tube 40. Obviously, the switching tube 40 may also be of the vacuum type, in which case the configuration of the keying pulses will determine the conducting interval of the switching tube.

Figure 7 illustrates a second application of a Thyratron type switching tube wherein a magnetron is energized by voltage from a constant potential source 60. A delay circuit 54 is inserted between the anode of the switching tube 40 and the cathode of the magnetron 50. When a positive keying pulse from the keyer 1 initiates the current discharge through the switching tube 40, the conducting path therethrough provides an effective short circuit on one end of the delay circuit 54. The positive potential which normally exists at the other end of the delay circuit 54 is reflected as a negative potential which is applied, at a later interval determined by the constants of the delay circuit, to reduce the potential on the anode of the switching tube 40, and thereby interrupt the current discharge therein. The magnetron is thereby de-energized until the next keying pulse is applied to the switching tube grid.

Thus the invention described comprises new and improved methods of and means for switching simultaneously a power circuit and a wave transmission circuit in response to pulses derived from a keying source.

I claim as my invention:

1. In a system of the type including a radio transmitter, a radio receiver, a source of operating potential for said transmitter, and a signal source for said receiver, the improvement comprising a duplex ionizable switching device comprising means defining a wave transmission path between said receiver and said signal source and means selectively providing a current discharge path transversely of said wave transmission path, and means including and operable upon said device for applying said operating potential to said transmitter and effectively isolating said receiver from said signal source, and for alternately effectively isolating said transmitter from said potential source and effectively coupling said receiver to said signal source.

2. In a system of the type including a radio transmitter, a radio receiver, a source of operating potential for said transmitter, and a signal source for said receiver, the improvement comprising a duplex ionizable switching device comprising means defining a wave transmission path between said receiver and said signal source and means selectively providing a current discharge path transversely of said wave transmission path, and means providing ionization of said device for applying said operating potential to said transmitter and effectively isolating said receiver from said signal source, and alternately providing de-ionization of said device thus effectively isolating said transmitter from said potential source and effectively coupling said receiver to said signal source.

3. In a system of the type including a radio transmitter, a radio receiver, a source of operating potential for said transmitter, and a signal source for said receiver, the improvement comprising a duplex ionizable switching device comprising a section of dielectric guide forming a wave transmission path between said receiver and said signal source and means selectively forming a gaseous discharge path transversely across said

guide, and means providing ionization of said device for applying said operating potential to said transmitter and effectively isolating said receiver from said signal source, and alternately providing de-ionization of said device thus effectively isolating said transmitter from said potential source and effectively coupling said receiver to said signal source.

4. In a system of the type including a radio transmitter, a radio receiver, a source of operating potential for said transmitter, and a signal source for said receiver, the improvement comprising a duplex ionizable switching device comprising a pair of resonant chambers, means providing a wave transmission path between said chambers for coupling said receiver to said signal source, said receiver and said source being coupled to different ones of said chambers, and means selectively forming a gaseous discharge path transversely across said coupling means of said resonant chambers to effectively isolate said chambers, and means providing ionization of said discharge path for connecting said operating potential to said transmitter and effectively isolating said receiver from said signal source, and alternately providing de-ionization of said device thus effectively isolating said transmitter from said potential source and effectively coupling said receiver to said signal source.

5. In a system of the type including a radio transmitter, a radio receiver, a source of operating potential for said transmitter, and a signal source for said receiver, the improvement comprising a duplex ionizable switching device comprising a pair of resonant chambers, means providing a wave transmission path between said chambers for coupling said receiver to said signal source, said receiver and said source being coupled to different ones of said chambers, and means selectively forming a spark discharge path transversely across said coupling means of said resonant chambers to effectively isolate said chambers, and means providing ionization of said discharge path for applying said operating potential to said transmitter and effectively isolating said receiver from said signal source, and alternately providing de-ionization of said device thus effectively isolating said transmitter from said potential source and effectively coupling said receiver to said signal source.

6. In a system of the type including a signal generator, a signal responsive device, a source of operating potential for said signal generator, and a signal source for said signal responsive device, a duplex keying device comprising the improvement comprising a current discharge device comprising means defining a wave transmission path between said receiver and said signal source and means selectively providing a current discharge path transversely of said wave transmission path, a source of keying pulses, a delay circuit, means connecting said delay circuit to said current discharge device, means connecting said operating potential source through said current discharge device and said delay circuit to said signal generator, means for applying said keying pulses to initiate said current discharge within said device for applying said operating potential to said signal generator and effectively isolating said signal responsive device from said signal source, and means including said delay circuit for alternately quenching said current discharge thus effectively isolating said signal generator from said potential source and effectively coupling said signal responsive device to said signal source.

7. In a system of the type including a signal

generator, a signal responsive device, a source of pulsating operating potential for said signal generator, and a signal source for said signal responsive device, the improvement comprising a duplex keying device comprising a gaseous discharge device comprising means defining a wave transmission path between said receiver and said signal source and means selectively providing a current discharge path transversely of said wave transmission path, a source of keying pulses, means responsive to said keying pulses for initiating a current discharge within said gaseous discharge device for applying said operating potential to said signal generator and effectively isolating said signal responsive device from said signal source, and means responsive to variations in said pulsating operating potential for alternately quenching said current discharge thus effectively isolating said signal generator from said potential source and effectively coupling said signal responsive device to said signal source.

8. A duplex current discharge switching device for use with a power circuit and a signal responsive device, said switching device comprising means including a pair of cooperating cavity resonators having coupling means providing a wave transmission path between said chambers for signals to said signal responsive device, means comprising a current discharge device disposed within said resonator coupling means and providing

30

a series path transversely through said coupling means for said power circuit, and means for initiating a current discharge in said current discharge device for completing said series path and effectively interrupting said signal transmission path for isolating said signals from said signal responsive device, and for alternately quenching said current discharge for interrupting said series path and effectively completing said signal transmission path.

9. A duplex current discharge switching device for use with a power circuit and a signal responsive device, said switching device comprising dielectric guide means providing a wave transmission path for signals to said signal responsive device, means comprising a gaseous discharge device disposed within said guide and providing a series path transversely of said guide for said power circuit, and keying means operable upon said gaseous discharge device for initiating a current discharge in said discharge device for completing said series path and effectively interrupting said signal transmission path for isolating said signals from said signal responsive device, and for alternately quenching said current discharge for interrupting said series path and effectively completing said signal wave transmission path.

MARTIN R. RICHMOND,
